COMBINATION T SQUARE, PROTRACTOR, CARD HOLDER, AND LETTER OPENER

Giles A. Baker, Scarsdale, N. Y.

Application May 26, 1954, Serial No. 30,678

Term of patent 14 years

(Cl. D52—1)

To all whom it may concern:

Be it known that I, Giles A. Baker, a citizen of the United States, residing in Scarsdale, county of Westchester, State of New York, have invented a new, original, and ornamental Design for a Combination T Square, Protractor, Card Holder, and Letter Opener, of which the following is a specification, reference being had to the accompanying drawing, forming a part thereof, in which:

Fig. 1 is a front elevational view of a combination T square, protractor, card holder, and letter opener, showing my new design;

Fig. 2 is a rear elevational view thereof;

Fig. 3 is a longitudinal cross-sectional view taken along line 3—3 of Fig. 1;

Fig. 4 is a transverse cross-sectional view taken along line 4—4 of Fig. 1;

Fig. 5 is a transverse cross-sectional view taken along line 5—5 of Fig. 1.

I claim:

The ornamental design for a combination T square, protractor, card holder, and letter opener, as shown.
